CLAIM

The ornamental design for a bottle opener keychain, as shown and described.

DESCRIPTION

FIG. 1 is a perspective view of the bottle opener keychain in closed position of the invention.

FIG. 2 is a right side elevational view of the bottle opener keychain of FIG. 1.

FIG. 3 is a left side elevational view of the bottle opener keychain of FIG. 1.

FIG. 4 is a front view of the bottle opener keychain of FIG. 1.

FIG. 5 is a back view of the bottle opener keychain of FIG. 1.

FIG. 6 is a top view of the bottle opener keychain of FIG. 1.

FIG. 7 is a bottom view of the bottle opener keychain of FIG. 1.

FIG. 8 is a perspective view of the bottle opener keychain of FIG. 1 with a partial magnified view thereon.

FIG. 9 shows the bottle opener keychain of FIG. 1 removing a cap from a bottle.

FIG. 10 is a right side elevational view of the bottle opener keychain of FIG. 1 in open position.

FIG. 11 is a right side elevational view of the bottle opener keychain of FIG. 1 showing a key hooked to the keychain; and,

FIG. 12 is a left side elevational view of the bottle opener keychain of the invention.

The broken line showing in the drawings are included for the purpose of illustrating portions of the bottle opener keychain and form no part of the claimed design.

1 Claim, 12 Drawing Sheets
